RESISTOR

Edmund Gilbert Lodge, Oak Lane, Pa., assignor
to Hugh H. Eby, Philadelphia, Pa.

Application February 20, 1931, Serial No. 517,161

3 Claims. (Cl. 201—63)

My invention relates to resistors, and particularly to fixed resistors used in radio circuits.

A purpose of my invention is to prepare standardized resistors by measuring the resistance included between the resistor contacts before the contacts are permanently affixed to the resistance winding and preferably while the resistor is still in place on the winding machine, and varying the position of the contacts until the desired resistance is obtained.

A further purpose is to simplify and improve the attachment of contacts to a resistance winding by electroplating the winding, desirably with copper, or some other metal easy to solder, adjacent to the points of attachment and soldering the contacts to the electro-plated surfaces of the winding.

A further purpose is to temporarily affix a contact to a resistance winding at the permanent position of the contact on the winding, and to electroplate the winding and subsequently solder the contact to the winding without intermediately disturbing the contact position.

A further purpose is to selectively electroplate the parts of a resistor at which contact to the resistor is to be made by passing current to the resistor in the plating bath at the points at which plating is desired, and maintaining the plating voltage low enough so that, due to the resistance of the resistor itself, the current density at points remote from those at which current enters the plating bath will not rise high enough to permit plating.

A further purpose is to tap a resistor by means of spring contacts secured at its extremities and also, if desired, at an intermediate point or points, soldering the contacts to the plated surface of the resistance winding.

A further purpose is to slot a contact to a resistor to facilitate soldering to the plated surface of the resistor.

A further purpose is to apply solder at spaced points on a fixed resistor determining the extent of solder application by the extent of preliminary treatment of the resistor.

A further purpose is to make contact to a resistance winding by caps which are soldered to an electroplated deposit upon the winding.

A further purpose is to use a solder band for clamping purposes to ensure good electrical contact with a fixed resistor.

Further purposes will appear in the specification and in the claims.

My invention relates both to the methods in-

volved and to apparatus by which the methods may be carried out.

In the drawing I illustrate only a few of the many variations in which my invention may be embodied, as well as diagrammatic illustrations of the apparatus required. The forms shown have been selected because of their ease of construction, satisfactory operation and convenient illustration of the principles involved.

Figure 1 is a perspective view illustrating my resistor in position upon a winding machine.

Figure 2 is an end elevation of the resistor of Figure 1 removed from the winding machine.

Figure 3 is a diagrammatic view of an electroplating bath showing my resistor in position for plating.

Figure 4 is a perspective view of my resistor after plating of the ends.

Figure 5 is a perspective view showing my resistor after soldering.

Figure 5a is a perspective view of a fragment of a bar.

Figure 6 is a fragmentary central vertical section of the soldered resistor.

Figure 7 shows a modified form of resistor in top plan view.

Figure 8 is a perspective view of a somewhat different form of resistor, showing the parts separated.

Figure 9 is a central vertical section of a resistor differing slightly from that of Figure 8.

In the drawing like numerals refer to like parts.

The radio manufacturer and the electrical industry generally demand a fixed resistor which, besides being mechanically sturdy has an accurately predetermined and reproducible resistance, because the design of the circuit as a whole and of the instruments in it presupposes a definite resistance. Much progress has been made in providing resistance wire of fairly uniform cross-section, but the connections to the resistance wire from the main circuit have not always been satisfactory either as to mechanical strength, contact resistance or accuracy of positioning.

In the past resistors have been prepared by winding the resistance wire on a form, regulating the pitch and length of the winding as accurately as commercial winding conditions will permit, and then securing to the winding contacts spaced a predetermined distance apart. Resistors prepared by this method will only be of the desired standard resistance if the resistance wire is of uniform cross section throughout, if the pitch of the winding is always uniform, if the

diameter of the form upon which the coil is wound is invariable and if the contact resistances are always the same. None of this is strictly true, so that as a result the fixed resistors heretofore prepared have varied considerably in resistance.

By my invention I permit accurate standardization of the resistors and eliminate most of the variables referred to above. After the winding is finished, I bridge it by the contacts which are to be permanently affixed to the resistor, but instead of initially making permanent attachment, I temporarily secure the contacts and measure the resistance across them, varying their distances apart until the resistance between the contacts is that desired for the standardized resistor.

Then, having temporarily affixed the contacts at the points desired for the predetermined resistance, I permanently secure them to the winding without intermediately changing the positions of the contacts. Once the resistance is standardized, no variation in resistance, or at most a very slight and definite variation, is subsequently permitted.

My method of attachment of the contacts to the resistor, while particularly suitable to a resistor which has been standardized by measurement of its resistance between contacts only temporarily secured to the winding, is also generally useful as a means of physical attachment of contacts to a resistance winding, whether or not the resistance has been previously measured.

The standardizing of a resistor is clearly illustrated in Figure 1. A winding 20 of suitable resistance wire, preferably a nickel chromium iron alloy of which one is very well known under the trade name of nichrome, is in position upon a winding machine. Of the winding machine the chuck 21 alone is shown with the wire 22 leading off to the supply spool of the machine. The chuck 21 rotatably supports a coil form 23, which I prefer to make of porcelain, or other ceramic material, desirably but not necessarily unglazed, as for example that sold under the trade name of "Isolantite". The form 23 may either be solid as shown in Figures 1, 2 and 4, or hollow, as shown at 23' in Figures 5 and 8. If the form 23 is not itself electrically insulating, I cover it with suitable insulating material.

At spaced points along the winding 20 I place metallic clip contacts 24 and 25, each of which comprises a slightly resilient curved gripping end 26 and a lateral extension 27, which is desirably provided with notches 28 and a hole 29 to assist in connecting to the external electric circuit. The gripping end 26 is preferably outwardly bent at its extremity 30 to assist in spreading its opposing sides when the clip contact is placed upon the winding. The gripping end 26 is longitudinally slotted at 31 to permit the introduction of solder and to facilitate electroplating as later explained.

After winding the coil 20 in any suitable manner, the clip contacts 24 and 25 are snapped upon the coil at spaced points as shown and current is passed from the contacts through the coil by connections 32 and 33 from a source 34. The circuit includes a suitable current-measuring instrument G upon which the resistance between the contacts 24 and 25 may be determined.

After the initial determination of the resistance, the spacing between the contacts 24 and 25 will if necessary be changed, either manually or mechanically, until the reading upon the cur-

rent-measuring instrument G indicates that the resistance between the contacts 24 and 25 has reached the correct value. Once this has been determined, the clip contacts 24 and 25 will be subsequently retained in their previous positions so that the resistance of the winding will not be changed after standardization.

While I believe that my method of standardizing the resistance of the resistor is in itself highly desirable, without regard to the means of permanent attachment of the contacts to the winding, and, in fact, without need of permanent attachment, I find that the method of permanent attachment invented by me greatly assists in placing the resistor in use without variation of its resistance subsequent to standardization. Of course my method of attachment is also applicable to resistors which are not standardized.

In Figure 3 I illustrate a conventional electroplating equipment comprising a vat 35 containing a solution 36 in which are located a suitable anode 37 connected to a current source through a lead 38 and a cathode 39 consisting of a resistance winding 20 electrically connected to the current source through the contacts 24 and 25, the 25 electrically conducting supporting frame 40 and the lead 41.

Since the resistance of the winding 20 is fairly high, and since current flowing from the lead 41 to the central portion of the winding 20 must 30 traverse the winding 20 from the nearer of the contacts 24 or 25, the current density upon the surface of the winding 20 rapidly decreases from a maximum at the ends 42 and 43, adjacent to the contacts 24 and 25, to a minimum at the center 44. By regulating the voltage between the plating terminals, I maintain the current density at the mid-portion of the winding 20 sufficiently low so that no plating takes place there while I have a high enough current density adjacent to 40 the contacts 24 and 25 so that plating takes place upon the winding at the ends 42 and 43.

It will readily be seen that plating of the portion of the winding 20 intermediate the contacts 24 and 25 would be undesirable as it would 45 coat the wire with an electrically conducting material and, especially where copper plating is used, would greatly reduce the resistance of the winding.

It will of course be evident that if electroplating were desired in any other localized zone of the winding other than the ends, it could be obtained by simply making contact to the winding in the plating bath at the point at which plating was desired.

To some extent the slit 31 in the gripping end 26 of the contact assists in plating by allowing free access of the plating solution to the resistance wire beneath the contact.

Plating with copper is particularly desirable 60 where the resistance wire used is nichrome, because soldering of nichrome wire is difficult, while soldering upon the copper-plated surface of the nichrome wire is relatively easy.

In practice I maintain a current density low 65 enough so that the only plating which takes place occurs upon the turns of the wire immediately adjacent to the contacts 24 and 25 and upon the surface of the contacts 24 and 25, particularly upon the inner surface of the curved 70 gripping ends 26 of the contacts 24 and 25.

Subsequent to plating I wash the resistor to remove all traces of the plating solution and dry it carefully before soldering.

Thus the juxtaposed surfaces of the contacts 75

24 or 25 and the winding 20 are electroplated as indicated in Figure 4, in which a thin covering of plating, preferably copper, is present upon the winding and the contacts at the ends 42 and 43.

5 After plating I solder the contacts, preferably by flowing molten solder through the longitudinal slits 31 of the contacts. The solder unites with the electroplated turns of the winding and with the contacts 24 and 25, thus firmly securing the contacts to the winding as seen in Figures 5 and 6. Solder is indicated at 45 around the turns of the winding 20 and between the winding and the gripping end 26 of the slip contact.

15 Where nichrome wire is used, the solder will not extend beyond the plated portion of the wire, so that there is no danger of short-circuiting by solder turns of the winding beyond the contacts.

20 The bar if made of some such material as nichrome, can, therefore, be plated or otherwise coated at the predetermined spacings and can then be flooded with solder to short-circuit the turns which are coated with (as in Figure 5) or without (as in Figure 5a) attachment of terminals at the time. It can then be sold in this condition for later use in connection with terminals or can have the terminals applied to it by the solder as part of the same operation or by subsequent soldering. Since the coated nichrome wire will take solder freely where coated and will not take it otherwise, the solder can be applied by dipping and automatically will be limited to the coated section. Moreover a solder covering about the wire (with or without prior coating of the nichrome to cause the solder to adhere to it) acts as a clamp to tighten the wire upon the mount as the solder contracts in cooling. This also tightens the solder about the wire, giving a good contact from the clamp action where there is any soldering.

40 The product will of course ordinarily be lacquered to make it water-proof and to hold the wire in place.

45 It will be noted that no change in the positions of the contacts 24 and 25 takes place subsequent to the final setting of the contacts during standardization of the resistance, and that no variation in the resistance of the winding between the contacts 24 and 25 is produced during permanent attachment of the contacts to the winding.

50 The only resistance change which is possible is a change in the contact resistance between the contacts 24 and 25 and the winding, and this I find to be very slight and to be nearly uniform for different resistors, so that allowance for it can be made in the original standardization.

55 My invention is by no means limited to securing contacts to the ends of a resistor. For example, in Figure 7 I illustrate an intermediate tap 46 which is fastened to the winding in the manner which I have outlined and whose position is determined by measurement of the resistance between the tap 46 and either of the contacts 24 and 25 in the manner previously discussed for positioning the contacts 24 and 25. In plating the resistor of Figure 7, contact is made at 24, 46 and 25.

60 My invention may also be applied to resistors of the cartridge type intended to be held by spring contacts. In Figure 8 I illustrate such a resistor winding 20 upon a hollow form 23, as well as contact caps 47 and 48. The extremities of the winding are plated as explained above, preferably after securing the caps upon the winding as shown in Figure 9, where the caps are in

position preparatory for plating. The caps may be provided either with open ends as in Figure 8, so that they may be moved along the winding to provide any desired space, or they may have closed ends as shown at 47' and 48' in Figure 9. The form of Figure 8 has the advantage that penetration of the plating solution into the interior of the caps occurs more readily.

65 While plating of the resistors when the contacts are in position is much preferable to plating before the contacts are applied, it will be understood that part of the advantage of my invention could be obtained by initially plating and subsequently applying the contacts. In that case, special contacts for use in the plating bath alone could be applied at the points at which the permanent contacts were to be affixed, and the plating contacts might then be removed to permit attachment of permanent contacts.

70 It will be evident that, by plating the parts in their final positions, I avoid shifting of the contacts subsequent to standardization, and insure that plating is restricted to the portion of the winding close to the contacts.

75 In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

80 Having thus described my invention what I claim as new and desire to secure by Letters Patent is:—

85 1. In a fixed resistor, a form, a winding upon the form of metallic resistance wire which takes solder with difficulty, a plurality of electrodeposited coatings upon the resistance wire over predetermined areas and at predetermined spacings along the wire, the extent of the wire between the spacings determining the resistance of the resistor, metallic contacts located at the electrodeposited areas and solder between the electrodeposited coatings and the metallic contacts, the distribution of the solder being restricted substantially to the electrodeposited areas and covering substantially the entire width of the electroplated areas, whereby the resistance at the contacts is reduced to a minimum and the resistance of the resistor is due to the predetermined spacing of the electrodeposited areas.

90 2. In a fixed resistor, a tubular form, a winding upon the form of metallic resistance wire which takes solder with difficulty, a plurality of areas of readily solderable metallic coatings upon the wire, the spacing between the areas being predetermined according to the desired resistance of the resistor, spring metallic contacts gripping the winding at the areas and solder between the contacts and the metallic coatings, the solder short-circuiting the turns at the coated areas for substantially the entire width of the coated areas and being substantially restricted in its distribution to the coated areas, whereby the resistance of the resistor is due substantially wholly to the predetermined spacing of the coated areas and the contact resistance is reduced to a minimum.

95 3. In a fixed resistor, a tubular form, a winding upon the form of metallic resistance wire which takes solder with difficulty, a plurality of areas of readily solderable metallic coatings upon the wire, the spacing between the areas being pre-

determined according to the desired resistance of the resistor, spring metallic contacts gripping the winding at the areas, each contact having a soldering opening adjoining its coated area and solder between the coatings and the contacts and along the edges of the openings through the contacts, the solder short-circuiting the turns at the coated areas and extending substantially for the axial extent of the coated

areas and the distribution of the solder being substantially restricted to the coated areas, whereby the uncertainty in resistor manufacture due to the contact resistance is reduced to a minimum and the reproducibility of the resistance is improved because the resistance of the resistor is due substantially wholly to the predetermined spacing of the coated areas.
